F. W. PLOSS

CLOSURE FASTENER

Filed Feb. 28, 1925

Inventor:

F. W. PLOSS

By Bealest Park

Attorney

UNITED STATES PATENT OFFICE.

FREDERICK W. PLOSS, OF PHILADELPHIA, PENNSYLVANIA.

CLOSURE FASTENER.

Application filed February 28, 1925. Serial No. 12,316.

To all whom it may concern:

Be it known that I, FREDERICK W. PLOSS, a citizen of the United States, residing at Philadelphia, in the county of Philadelphia and State of Pennsylvania, have invented 5 certain new and useful Improvements in Closure Fasteners; and I hereby declare that the following is a full, clear, and exact description thereof, reference being had to the accompanying drawings, which form part 10 of the specification.

My invention consists in a closure fastener for doors and more particularly for automobile doors and bodies. My device is 15 a dove-tail adapted to be attached to a door jamb and to receive a projection or tongue attached to the door, in such a manner as to keep the door well balanced on its hinges by the resilient contact thus formed between 20 the door and the door jamb.

One advantage of my device is the type of 25 full elliptical springs which surround a rubber cushion in such a manner as not to compress the rubber, thus no initial compression, which would harden the rubber is exerted upon this resilient cushion.

Another advantage appears in the elliptical 30 spring reinforced by rubber. This construction allows the quickly acting spring to withstand the constant shocks to which it is subjected by the tortions to which an automobile door is constantly subjected. Also the shock of closing the door is well taken care of by the elliptical type spring, reinforced by a resilient cushion of rubber.

It has been found in practice that a long 35 life may be expected from elliptical type springs reinforced by rubber.

Referring to the drawings:

40 Fig. 1, is a plan view of my closure fastener.

Fig. 2, is a side view of my device showing the tongue engaged therewith.

45 Fig. 3, is a cross section taken on the line 3—3 of Fig. 1.

Fig. 4, is a cross section on the line 4—4 of Fig. 1.

Fig. 5, shows a side view of the rubber cushion.

Fig. 6, shows my elliptical spring.

Referring more particularly to the drawings 50 10 denotes a flange of my casing 11 adapted for attachment to a door jamb having countersunk screw holes 12. The casing has an open face 13 and an open front 14. 55 The case 11 is provided with inwardly protruding portions 15 adapted to normally hold the rubber cushions 16 in place. Surrounding or encasing each rubber cushion is an elliptical spring 17. A plate 18 having 60 countersunk screw holes 19 is provided for attachment to a door, and provided with a tongue 20 adapted to engage the springs 17 when the door is closed.

Having pointed out the novel construction, combination and arrangement of my parts, what I wish to claim and secure by Letters Patent is:—

1. In a closure fastener the combination 65 of a casing consisting of a box having an outwardly extending rim; a cover plate having an opening therein, said plate being adapted to engage said extending rim and two springs the ends of each being adapted to virtually meet, said meeting ends of each 70 spring being adapted to abut the same side respectively of the box.

2. In a closure fastener the combination 75 of a casing consisting of a box having an outwardly extending rim; a cover plate having an opening therein, said plate being adapted to engage said extending rim; two cushions positioned in said box; means in the bottom of said box adapted to engage 80 said cushions; and two springs adapted to virtually enclose respectively said cushions, the ends of each spring being adapted to virtually meet, said meeting ends of each 85 spring being adapted to abut the same side respectively of the box.

90 In testimony that I claim the foregoing as my own, I affix my signature.

FREDERICK W. PLOSS.
